BALING PRESS.

No. 604,324.

Patented May 17, 1898.

UNITED STATES PATENT OFFICE.

JULIUS H. HOLMGREEN, OF SAN ANTONIO, TEXAS.

BALING-PRESS.

SPECIFICATION forming part of Letters Patent No. 604,324, dated May 17, 1898.

Application filed October 4, 1897. Serial No. 654,076. (No model.)

To all whom it may concern:

Be it known that I, JULIUS H. HOLMGREEN, a citizen of the United States, residing at San Antonio, in the county of Bexar, in the State of Texas, have invented certain new and useful Improvements in Baling-Presses, of which the following is a full, clear, and exact description, such as will enable those skilled in the art to which it appertains to make and use the same, reference being had to the accompanying drawings, which form a part of this specification.

This invention relates to improvements in baling-presses of that class in which a platen is reciprocated back and forth in a baling-chamber into which the material to be compressed is intermittently fed between the strokes of the platen and the whole mass compressed by successive impacts.

It relates more particularly to improvements in the modulating mechanism whereby the platen is operated and by means of which the platen is moved at a gradually-decreasing rate of speed into the baling-chamber and at the same time with an increasing force.

The invention especially relates to certain improvements in the mechanism for conveying power from an operative means to the plunger carrying the platen.

The invention has for its object the provision of a gear mechanism consisting of a rack in the form of a compound curve and a spiral gear meshing with said rack, constructed so that the gear and rack will always be in engagement, and thereby avoid the breaking of teeth by improper registration, whereby the plunger can have a rigid connection with the platen and be reciprocated in a line parallel with the axis of the baling-chamber, and the provision of a mechanism whereby the driving mechanism can be continuously rotated and from which power can be transmitted to the spiral gear to rotate the latter to a limited extent and to automatically release said gear from the said operative mechanism intermittently to allow the plunger to be withdrawn from the baling-chamber.

The invention consists in the novel construction, combination, and arrangement of parts, such as will be hereinafter fully de-

scribed, pointed out in the appended claims, and illustrated in the accompanying drawings.

55

In the accompanying drawings, in which similar letters of reference designate corresponding parts, Figure 1 is a side elevation, broken away in parts, of a baling-press embodying the invention, showing the plunger 60 carrying the platen at the beginning of a stroke. Fig. 2 is a plan view of the same. Fig. 3 is an enlarged detail view showing a plan of the modulating-gear mechanism. Fig. 4 is an enlarged detail view, partly in 65 elevation and partly in section, of the mechanism intermediate of the sweep and the plunger. Fig. 5 is a plan view of the machine, showing the positions of the several parts at the end of a stroke of the plunger. 70 Figs. 6 and 7 are detail sectional views showing the trip-dog.

Referring to the drawings by letter, A designates the baling-chamber, mounted on the base A', carried by the wheels A''. As these 75 several parts may be of any construction suitable in the premises and well known in the art, they need not be particularly described.

In the baling-chamber A is mounted the platen B, secured to the plunger B', by which 80 it is reciprocated back and forth. The plunger has a rigid connection with the platen and moves in a line parallel with the longitudinal axis of the baling-chamber. By having the plunger moving in this way the power is 85 applied directly to the platen and directly against the resistance offered by the material being compressed. Furthermore, as the plunger moves back and forth in the same line there is no liability of it becoming cramped 90 in the baling-chamber, as there would be if the plunger were in the form of a pitman hinged to the platen and provided with an operating mechanism that oscillated the same as the said mechanism moved the said plunger back 95 and forth, and also the depth of the baling-chamber is not limited by the rigid non-oscillating plunger, as it would be if a pitman having considerable oscillation were used, for in the latter instance the pitman could be introduced so far into the baling-chamber as not 100 to come in contact with the sides of the latter.

A mechanism is provided for reciprocating the plunger back and forth in a line parallel

with the axis of the baling-chamber. This mechanism operates to move the plunger quickly, comparatively, at the beginning of the stroke, where the resistance offered by the material being compressed is the least, and to gradually decrease the speed of the stroke as the plunger moves into the chamber and as the resistance increases and at the same time operates to gradually increase the force 10 with which the plunger is moved.

On the end of the base A' farthest from the baling-chamber is secured the plate C, provided with the socket or bearing c'. Mounted on the plate C and secured thereto in any 15 suitable manner is the frame or support c², having a bearing c³ immediately above and concentric with the bearing or socket c' in the said plate. A shaft c⁴ is journaled in the bearing c³ of the support c² and has its reduced lower end seated or journaled in the socket or bearing c' in the plate C.

A gear D is keyed on the shaft c⁴ intermediate of the plate C and the support c². The formation of this gear is such that the distances between its teeth and its axis gradually vary, so that the said teeth form substantially a volute or spiral curve. This gear meshes with the rack E, mounted on the plunger B'. The said rack is formed on the edge 20 of the plate, secured on the upper face of the plunger in any suitable manner. The outline of the rack is such as to mesh with the gear D and at the same time move the plunger in a straight line. The line followed by 25 the teeth of the rack is substantially a serpentine or compound curve.

A device is provided for holding the rack in mesh with the gear. Between the projection c⁵ of the plate C and the projection c⁶ of 30 the support c² is journaled the roller c⁷. The latter bears on the side of the plunger farthest from the gear D, and thereby prevents the movement of the plunger away from said gear.

A mechanism is provided for partly rotating the shaft c⁴ and through the intervening gearing for reciprocating the plunger. On the upper end of the shaft c⁴ a yoke H is journaled. This yoke consists of the plate h, bolted to the under side of the sweep H', the 45 plate h', and the intervening casing h². The plates and casing are held together by the bolt h⁸ passing through them. The yoke is free to rotate on the shaft c⁴ and is carried around the latter by the sweep H'. The plate 50 h' rests on the support c², and the plate h has formed in its under face a socket or bearing h⁴, in which is journaled or seated the upper reduced end of the shaft c⁴. In the casing h² a trip-dog is mounted and is retained therein by the bolt h⁹. The trip-dog consists of the cylindrical portion h⁵, from which projects the trip h⁶ and the dog h⁷ in opposite 55 directions. The trip h⁶ extends through an opening h⁸ in the casing and projects to a considerable distance beyond the latter. The dog h⁷ projects inwardly from the casing and

in advance of the yoke. The trip-dog is held in its normal position by the spring h⁹.

A driver K is mounted between the plates h and h' of the yoke and is keyed on the shaft 70 c⁴. The length of the driver is such to allow it to pass through the yoke. In a recess formed in the outer end of the driver a roller k' is journaled. The roller is carried in such a position by the driver as to be engaged by 75 the dog h⁷ when the yoke is moved by the sweep. To disengage the dog from the driver, a pin k² is mounted on the extension c⁶ of the support c². Against this pin the trip h⁶ strikes and throws the dog h⁷ out of engagement with the roller k', and thereby releases the 80 yoke from the driver.

The operation of the device is as follows: The sweep H' is moved in the direction indicated by the arrow in Fig. 2. As the yoke H is secured to the said sweep it is rotated on the shaft c⁴. In its rotation on the shaft the dog h⁷, carried by the said yoke, engages with the roller k' and thereby moves the driver K with the yoke. As the driver K is keyed on the 85 shaft c⁴, the latter is also rotated. This rotation of the shaft c⁴ also rotates the spiral or volute gear D, also keyed on the said shaft. As the spiral gear is rotated through its engagement with the rack E the plunger is 90 forced into the baling-chamber. The relative arrangement of the spiral gear and the curved rack E is such that the teeth farthest from the axis of the spiral gear engage with the rack first. This engagement takes place 95 when the plunger is at the beginning of its forward stroke and when the material in the baling-chamber is the least compressed and when the resistance to the movement of the platen is also the least. The first movement 100 of the plunger is the quickest, comparatively, as the gear-teeth then operating move in longer arcs of circles having longer diameters than those nearer the axis of the gear. It is

to be observed that the plunger has less force 110 at the beginning of the stroke, owing to the comparatively longer leverage of the gear-teeth then in engagement. This comparatively lacking of force with which the plunger acts at the beginning of its stroke is compensated for by its comparatively quick movement. As the material offers its least resistance at the first part of the stroke, the forward movement of the platen will not be resisted to the same extent as it will be as the 115 plunger advances into the baling-chamber. As the rotation of the spiral gear continues, the teeth, moving in arcs of gradually-decreasing lengths in circles of gradually-lessening diameters, engage with the rack. Consequently the forward movement of the plunger gradually becomes slower, and as the leverage between the gear and the rack decreases the force with which the plunger acts 120 gradually increases. This increase of force 125 is met by the gradual increase in the resistance offered by the material being compressed. 130

In this way a plunger-operating device is secured in which the resistance to the movement of the sweep is comparatively regular. As the driver K, engaged with the yoke H by the trip-dog, moves with the yoke until the plunger reaches the end of its forward stroke, the trip h⁶ strikes the pin k² and disengages the dog h⁷ from the said driver and releases the latter from the yoke. The plunger is forced back to its original position by the elasticity of the material being compressed and the spring S. As the rack always engages with the spiral gear and as the shaft on which the latter is keyed is free, the said gear will also be returned to its original position and in readiness for another forward movement of the plunger.

It is to be observed that the rack and spiral gear are always in engagement and always in their proper relative positions. This obviates the difficulty which would be involved in securing a proper registration of the two parts if they should be separated at the end of each stroke. This preserves the teeth from being broken by improper registration.

The herein-described embodiment of the invention is the preferred one, yet it can be departed from to a considerable extent without departing from the spirit of the invention.

Having thus described my invention, what I claim, and desire to secure by Letters Patent, is—

1. In a baling-press, the combination of a platen, a plunger connected with said platen, a rack mounted on said plunger, a rotatable shaft, a gear fixed on said shaft and engaging with said rack, a yoke journaled at its open end on said shaft, means for rotating said yoke on said shaft, a driver fixed on said shaft between the forks of said yoke and adapted to move clear of the yoke, a dog pivoted in the bifurcation of said yoke for engaging with said driver, and a trip for disengaging said dog from said driver.

2. In a baling-press, the combination of a platen, a plunger connected with said platen, a rack mounted on said plunger, a rotatable shaft, a gear fixed on said shaft and engaging with said rack, a yoke having its forks connected by a casing journaled at its open end on said shaft, means for rotating said yoke on said shaft, a driver fixed on said shaft between the forks of said yoke and adapted to move clear of said casing, a dog pivoted in said casing and adapted to engage with said driver, and a trip for disengaging said dog from said driver.

3. In a baling-press, the combination of a platen, a plunger rigidly connected with said platen and moving in a line parallel with the axis of the baling-chamber, a rack mounted on said plunger and having its teeth following a line in the form of a compound curve, a rotatable shaft, a spiral gear secured on said shaft and in continuous engagement with said rack, a yoke journaled at its open end on said shaft, means for rotating said yoke on said shaft, a driver fixed on said shaft between the forks of said yoke and adapted to move clear of the yoke, a dog pivoted in the bifurcation of said yoke for engaging with said driver, and a trip for disengaging said dog from said driver.

4. In a baling-press, the combination of a platen, a plunger rigidly connected with said platen and moving in a line parallel with the axis of the baling-chamber, a rack mounted on said plunger and having its teeth following a line in the form of a compound curve, a rotatable shaft, a spiral gear secured on said shaft and in continuous engagement with said rack, a yoke having its forks connected by a casing and journaled at its open end on said shaft, means for rotating said yoke on said shaft, a driver fixed on said shaft between the forks of said yoke and adapted to move clear of said casing, a dog pivoted in the said casing and adapted to engage with said driver, and a trip for disengaging said dog from said driver.

5. In a baling-press, the combination of a platen, a plunger connected with said platen, a rack mounted on said plunger, a plate provided with a bearing, a shaft journaled at an end in said bearing, a gear fixed on said shaft and engaging with said rack, a roller-bearing on said plunger for holding said rack and said gear in engagement, a yoke having its forks connected by a casing and journaled at its open end on said shaft, means for rotating said yoke on said shaft, a driver fixed on said shaft between the forks of said yoke and adapted to move clear of said casing, a roller journaled in the outer end of said driver, a dog pivoted in said casing and adapted to engage with the roller carried by the driver, and a trip for disengaging said dog from said roller.

In testimony whereof I hereunto affix my signature in the presence of two witnesses.

JULIUS H. HOLMGREEN.
